UNITED STATES PATENT OFFICE.

LUCIEN JOSEPH GESCHWIND, OF PARIS, FRANCE, ASSIGNOR TO STÉ A^e DES MANUFACTURES DE PRODUITS CHIMIQUES DU NORD-ETABLISSEMENTS KUHLMANN, OF PARIS, FRANCE, A FRENCH CORPORATION.

MECHANICALLY-OPERATED FURNACE FOR ROASTING PYRITES.

Application filed June 29, 1921. Serial No. 481,345.

To all whom it may concern:

Be it known that I, LUCIEN JOSEPH GESCHWIND, a citizen of the French Republic, residing at Paris, France, have invented certain new and useful Improvements in Mechanically-Operated Furnaces for Roasting Pyrites, of which the following is a specification.

This invention relates to a mechanically operated furnace for roasting pyrites or like ores containing sulphur, of the known type comprising stationary soles and a central revoluble shaft, and affording for a given surface of sole a roasting efficiency which is much superior to that of the known furnaces. In order to obtain this result it is essential to make use of all the soles of the furnace to their maximum extent, this being secured by a feeding which is quite constant and is adjustable according to the character of the material employed, as well as by a uniform distribution of the material over the various soles when starting from the first sole. The mass thus uniformly distributed is likewise required to be roasted in a complete and uniform manner, and this can only be obtained by a rabbling which will not occasion an unduly rapid propulsion of the material and will also overturn the prismatic mass of the latter, besides leaving the different masses quite independent of each other during the process of roasting, each mass corresponding to the region of action of a tooth of the rabbling rake.

But up to the present time, the known devices have not been able to provide for a perfectly regular feed of the ore, chiefly by reason of frequent clogging or caking of the ore within the feeding hoppers, and furthermore, no special device was provided to secure the equal distribution of the ore upon the soles, as it was considered that this distribution was sufficiently afforded by the rabbling rakes. However the various investigations which I have carried out relative to this subject have proved that such rakes possess but a small tangential reaction and that for this reason they are useful only as members for radial propulsion and not as distributing members. In fact, observations made upon the furnaces now in use lead to the conclusion that it is only after the fourth sole that a reasonably good

distribution is obtained; furthermore, none of the forms of rake hitherto proposed will afford the desired result as hereinbefore stated.

In the furnace according to my invention, these objects are attained in the following manner. The feeding of the ore is effected by the use of an impact feeding device disposed at the bottom of a wide-mouthed hopper serving for the admission of the material and comprising an inclined movable member adapted to receive the impact of a striker provided with a suitable adjustment for the amount of swing and the frequency of the shocks. The shocks thus produced are employed to discharge the ore into the furnace, and it is delivered upon the upper sole; the ore is thus prevented from clogging at the discharge end of the hopper, as is the case with the known devices. To obtain a uniform distribution of the pyrites starting with the first sole, the central shaft passing through the furnace from top to bottom has disposed upon the upper part thereof a pair of inversely directed helical feeding trough or spouts for receiving the stream of ore as delivered from the feeding device and for distributing this ore in a ring-shaped mass upon the upper sole whence it is caused to descend to the succeeding soles.

The combined stirring and propulsion, or the rabbling action, is carried out upon each sole by means of a single rake or a pair of oppositely situated rakes secured to the central shaft and provided with teeth having the form of a mould-board of a plough which engages with the mass of ore in an approximately vertical position, the disengaging angle being substantially equal to the natural falling angle or bank of the pyrites. Furthermore, all the teeth secured either to a single rake or to a pair of oppositely situated rakes are so disposed as to follow each other in a continuous series, thereby making use of the entire sole.

The furnace according to this invention likewise presents a number of characteristic details of construction which will be described hereunder.

The accompanying drawings show by way of example an embodiment of my invention.

Fig. 1 is a general view of the furnace in section and in elevation.

Fig. 2 is a view of the feeding device on a larger scale.

Figs. 3 and 4 are elevational and plan views of the device for distributing the pyrites upon the upper sole.

Fig. 5 is a diagrammatic view showing the arrangement of the teeth upon a single rake.

Fig. 6 is a diagrammatic view of a tooth of the said rake in elevation and plan.

Fig. 7 is a diagrammatic view of the disposition of the teeth upon two oppositely situated rakes.

Figs. 8 and 9 are elevational and plan views of the helical passages provided in the walls of the furnace.

Figs. 10 and 11 are elevational and plan views of the gas passages provided in the walls of the furnace.

The furnace is constituted by a cylindrical chamber 1 having therein a series of stationary soles disposed in tiers, the bottom of each sole serving as a roof for the sole which is situated thereunder. A roof 3 is disposed above the upper sole. The chamber 1 is traversed throughout its entire height by a revoluble shaft 4 which is actuated by the shaft 5 through the intermediary of the driving device 6. The speed of the driving 25 may be modified and regulated by means of known devices which are not shown. The shaft 4 is provided above each sole within the constructional form represented as an arm 7 whose function will be described here- 30 under. In Fig. 1, only the inner ends of the said arms 7 have been represented, save for one of the arms which is entirely shown.

The main gear wheel actuating the shaft 4 is provided with a flanged edge portion 40 constructed of thin cast iron or sheet iron 41 which cooperates with the walls of the chamber 1 to form a trough for conducting into the discharge aperture 8 the roasted residues falling from the peripheral portion of the last sole. The air used for the purpose 45 of facilitating combustion is admitted through the lower part of the furnace at 8. The feeding of the furnace with pyrites is effected at the top of the furnace in the following manner. The pyrites Figs. 1 and 2, are poured into the hopper 9 ending at the lower part thereof in a mouth of large section 10. The said hopper is disposed upon a closed casing 11, provided with a door 12 and a neck 13, and ending at the lower part 50 in a spout 14 engaging the upper part of the chamber 1. Below the mouth 10 is disposed an inclined movable member 15 which is strengthened at the rear part thereof by a thrust plate 16; the said movable member is suspended from the casing 11 by four articulated links 17 which may be replaced without inconvenience by rigid rods. The said neck 13 is traversed by an impact rod 18 55 whose head 19 is maintained upon its seat

by a spring 20 the tension whereof is adjustable by means of the nut 21. A striking member 22 is pivoted at 23 to the hopper 9 and carries a rod 24 whereon are loosely disposed the washers 25 forming a suitable weight and serving to regulate the said striker. A wheel with four cams 26 rotating at slow speed provides for the lifting and the sudden fall of the striker 22 upon the impact rod 18. At each stroke, a certain quantity of pyrites is caused to fall from the movable member 15, thus causing the pyrites to be discharged through the spout 14 into the body of the furnace. This affords a very regular distribution of the pyrites without stoppage or accumulation of the material, inasmuch as the cohesion of the mass is entirely destroyed by the jarring produced by the shock of the striker.

When discharged from the spout 14, the pyrites fall into one or the other of the two helical collars disposed in the contrary sense 27, 28, and mounted upon the revoluble shaft, Figs. 3 and 4. The said collars form discharge spouts and are so constructed as to be readily removed. By reason of the rotation of the shaft, the pyrites will be fed upon the upper sole 2 in the form of a continuous and regular ring which is acted upon by the rakes carried upon the arms 7. The soles 2 have the form which is shown in Fig. 1. The upper part thereof is constituted by a number of annular steps, the under part 30 being cone-shaped.

In order to provide a disposition wherein the said soles shall be situated in proximity to each other while at the same time giving to the said rake a sufficient height of teeth as well as the amount of play which is required for its proper operation, the upper edge 31 of the arm 7 is made oblique and parallel to the generatrices of the cone 30. The stepped annular form which is given to the upper surface of the sole will provide a horizontal plane for the rabbling action without requiring the same thickness of sole which would be necessary if a plane upper surface were employed. The arm 7 actuated by the shaft 4 carries the rabbling rakes which move the pyrites from one level to the other in an alternate manner at the periphery and at the centre of the soles. The teeth of the said rake are therefore disposed alternately from one level to another in such manner as to afford respectively a centrifugal and a centripetal action, as is usual in furnaces of this class. In the constructional form represented in Figs. 1 and 5, each tier contains only a single arm; each of the arms 7, Fig. 5, carries a set of teeth 32 disposed in a continuous manner, the end situated farthest from the centre of the furnace in one tooth being disposed on the same circle as the end adjacent the centre in the succeeding tooth. The inclination of 120

the said teeth, which are disposed parallel to each other by a method of construction shown in Fig. 5, is about 66° , in such manner as to obtain at the rear of the teeth a considerable spacing which will prevent clogging of the device. On the contrary to the arrangements hitherto employed, the teeth have the form of a mouldboard of a plough, as shown in plan and elevation in Fig. 6. 10 These teeth 32 attack almost vertically the mass of pyrites 47 (indicated in dotted lines) thrown back by the adjacent tooth and leave the mass at an angle which is substantially equal to the natural falling angle 15 of the mass of pyrites, that is to say about 45° . The teeth by turning over the mass 8 constitute by the side of the mass 8 another mass 9 which will be in turn treated by the following tooth. In this manner an efficient stirring action is obtained. The mass which is raised against the said teeth is impelled in the forward direction; no falling slope or bank is formed at the rear part, and the prism formed by the mass of pyrites 25 is overturned at each of its points.

Moreover, the masses of pyrites corresponding to each tooth will remain absolutely independent of each other during the process of roasting. It will be observed that this 30 result cannot be attained by the use of known shapes of teeth which are entirely flat, nor even with teeth in the form of a plough-share acting after the manner of a spoon as has been proposed by some inventors. In 35 fact with such teeth the mass of the pyrites is compressed between the blades and becomes raised up, and when leaving these members it rolls down in such manner that a portion of the material is covered by the 40 banked material brought forward by the succeeding blade. This will give rise to a mixture of the masses which are in course of propulsion, and as the mass is not overturned, the mixing action will be defective, 45 since by reason of the rolling down of the mass, the same particles will remain at the surface and at the centre. The teeth having the shape of a ploughshare will afford a slightly better stirring without obviating 50 these drawbacks.

As the rakes which act in centrifugal direction are subjected to much greater resistance stresses than the rakes which act in centrifugal direction, it is advantageous to 55 give them a special form.

Instead of using a tooth of a triangular shape as is represented by the full lines in Fig. 6, it is preferable to give to its straight section on the sole a curve such as that 60 shown in dotted lines. It is clear that when the tooth progresses in the direction of the arrow F, the resistance to forward movement is less for the curve 50 than for the straight line 49. In fact if this resistance is slightly 65 higher for the curve towards the front part

of the curve, this increase in resistance is without great importance for in this part, as can be seen by the elevation 8 of the mass of pyrites, the penetration of the tooth is easily effected. On the contrary towards 70 the rear, as the mass of pyrites displaced is greater, the curve 50 becomes nearer than the straight line 49 to the circumference about which is effected the rotation of each of its points and consequently the resistance to 75 forward movement of this curve is less. The teeth of rakes which act on a centripetal direction can be of much simpler formation as long as they keep the form of a mould board of a plough which is the characteristic of the system, it is unnecessary to give them the curvature described above. 80

Instead of employing a single rake for each tier, two oppositely disposed rakes may be employed which are provided with teeth 85 of the same shape as herein described, but in this case the inclination of the said teeth with reference to the rake is only half what is used in the former case, and the teeth are alternately disposed upon one of the racks 90 and the opposite rack, this arrangement being shown in Fig. 7.

Upon the opposite arms 35 and 36 are disposed the teeth whereof the angle of inclination with reference to the rake is one-half the value of the inclination of the tooth 32 with reference to the rake 7, Fig. 5. Taking into consideration a tooth 37 disposed upon the rake 35, the end of the said tooth which is situated farthest from the 95 centre of the furnace is located on the same circle as the end of the tooth 38 which is situated nearest the centre of the furnace, this latter tooth being one of the set disposed upon the arm 36. In like manner, the end 100 of this latter tooth which is situated farthest from the centre of the furnace is located upon the same circle as the end of the following tooth 39—carried by the rake 35—which is situated nearest the centre of the 105 furnace, and so on.

It will be observed that the results obtained by the arrangement shown in Figs. 1 and 5 are also obtained by the use of the above-mentioned device. Furthermore, instead of moving forwardly through a complete pitch distance for each revolution of the rake, the mass of pyrites moves forwardly 115 by two operations to cover one-half the pitch distance at each operation. By this means a particularly efficacious roasting of the ore is obtained. Moreover, in the case of ores having a tendency to agglomerate by melting, this will afford a means for breaking the crust which is formed. On the other hand, by reason of the lesser inclination of the teeth, the effect of clogging is obviated to a considerable degree. To reduce to a minimum the amount of dust given off during the descent of the pyrites, this dust 120

being prejudicial to the proper roasting, the following device has been provided for the downward movement at the periphery. The odd numbered soles 2 are provided with the 5 incline planes 40, Figs. 8 and 9, which are suitably spaced around the periphery; within the walls of the chamber 1 are formed the helical passages 42 opening opposite the said inclined planes for conducting the material 10 to the sole situated immediately thereunder, a raised portion 43 being provided upon the periphery of the latter in such manner as to form a triangular prism constituted by the falling of the material and the rake under 15 centripetal action at this level is caused to engage with the said material. The passages 44 passing through the wall of the chamber 1 are used to clear out the said passages 42, should this be required.

20 To convey the material from an even numbered sole to an odd numbered sole situated immediately thereunder, the even numbered sole has formed at the centre a funnel-shaped aperture 45. An arrangement may likewise be employed for dust-reducing purposes wherein suitable passages are disposed opposite the said apertures 45 on the shaft 4 for conducting the pyrites to the lower sole. In order to prevent hot 25 gases rising through the furnace from passing through and drawing along the dust, a separate path is afforded for the same, as is already known. To this effect the walls of the chamber 1 have disposed therein the 30 passages 46 which are caused to open at a higher level than the opening of the helical passages 42. The said passages constitute a path of least resistance for the gases which will have a strong flow through the same 35 and will therefore be prevented from passing through the dust.

What I claim is:

1. In a furnace mechanism for roasting pyrites, having fixed stepped hearths, a 45 central rotating shaft and a rake carried by the shaft, teeth carried by the rake being in the form of plough mold boards.
2. A mechanically operated furnace for roasting pyrites provided with stationary soles disposed in tiers and a central revoluble shaft having mounted thereon the rabbling rakes, a wide-mouthed hopper, a closed receptacle supporting the said hopper and entering the upper part of the furnace, a laterally movable member disposed in an inclined position under the discharge aperture of the said hopper, a striker acting upon the said movable member, a hammer actuating the said striker, a cam shaft controlling the swing of the said hammer, a device for adjusting the weight of the said hammer, a double helical spout disposed upon the central shaft between the inclined laterally movable device and the first sole of the furnace, two oppositely-directed rabbling arms disposed at each tier and teeth having the shape of the mould board of a plough, the 50 55 60 65

said teeth being situated parallel to each other in a continuous row and obliquely disposed with reference to the arm.

3. A mechanically operated furnace for roasting pyrites provided with stationary soles disposed in tiers and a central revoluble shaft having mounted thereon the rabbling rakes, comprising in combination a device for regular and adjustable feeding which is actuated by the effect of shocks, a double helical spout disposed upon the central shaft between the feeding device and the upper sole, rabbling arms provided at each tier, and teeth having the shape of the mould board of a plough, the said teeth being situated parallel to each other in a continuous row and obliquely disposed with reference to the arm.

4. A mechanically operated furnace for roasting pyrites provided with stationary soles disposed in tiers and a central revoluble shaft having mounted thereon the rabbling rakes, comprising in combination a device for regular and adjustable feeding which is actuated by the effect of shocks, a device for the regular distribution of ore upon the first sole of the furnace, two oppositely-directed rabbling arms disposed at each tier and teeth having the shape of the mould board of a plough, the said teeth being situated parallel to each other in a continuous row and obliquely disposed with reference to the arms, and so arranged that for a given tooth carried by one of the said rakes, the end of the said tooth which is situated farthest from the centre of the furnace shall be located on the same circle as the end nearest the centre of the furnace of the following tooth of the oppositely situated rake, and so on.

5. A mechanically operated furnace for roasting pyrites provided with stationary soles disposed in tiers and a central revoluble shaft having mounted thereon the rabbling rakes, a wide-mouthed hopper, a closed receptacle supporting the said hopper and entering the upper part of the furnace, a laterally movable member disposed in an inclined position under the discharge aperture of the said hopper, a striker acting upon the said movable member, a hammer actuating the said striker, a cam shaft controlling the swing of the said hammer, a device for adjusting the weight of the said hammer, a double helical spout disposed upon the central shaft between the inclined laterally movable device and the first sole of the furnace, two oppositely-directed rabbling arms disposed at each tier and teeth having the shape of the mould board of a plough, the said teeth being situated parallel to each other in a continuous row and obliquely disposed with reference to the arms and so arranged that for a given tooth carried by one of the said rakes, the end of the said tooth 105 110 115 120 125 130

which is situated farthest from the centre of the furnace shall be located on the same circle as the end nearest the centre of the furnace of the following tooth of the oppositely situated rake, and so on.

6. A mechanically operated furnace for roasting pyrites provided with stationary soles disposed in tiers and a central revoluble shaft having mounted thereon the rabbling 10 rakes a wide-mouthed hopper, a closed receptacle supporting the said hopper and entering the upper part of the furnace, a laterally movable member disposed in an inclined position under the discharge aperture of the said hopper, a striker acting upon the said movable member, a hammer actuating the said striker, a cam shaft controlling the swing of the said hammer, a device for adjusting the weight of the said hammer, a double helical spout disposed upon 20 the central shaft between the inclined lat-

erally movable device and the first sole of the furnace, two oppositely-directed rabbling arms disposed at each tier and teeth having the shape of the mould board of a plough, 25 the said teeth being situated parallel to each other in a continuous row and obliquely disposed with reference to the arms, and so arranged that for a given tooth carried by one of the said rakes, the end of the said tooth which is situated farthest from the centre of the furnace shall be located on the same circle as the end nearest the centre of the furnace of the following tooth of the oppositely situated rake, and so on, and helical spouts provided in the walls of the furnace for the lateral descent of the pyrites from one tier to another. 35

In witness whereof I have hereunto set my hand.

LUCIEN JOSEPH GESCHWIND.
